UNITED STATES PATENT OFFICE

WALTER H. MORRIS, OF IPSWICH, SOUTH DAKOTA

AUTOMATIC TIME CONTROLLED SAFE LOCK

Application filed September 22, 1930. Serial No. 483,663.

This invention appertains to new and useful improvements in safe locks and more particularly to a mechanism whereby a safe door can be secured against movement for a predetermined period.

An important object of the invention is to provide a safe locking mechanism capable of being set to become released within a predetermined period at any future moment.

These and other objects and advantages of the invention will readily become apparent to the reader of the following specification and claims.

In the drawings:—

Fig. 1 represents a front elevational view of a safe, showing partly in section, the mechanism of the invention.

Fig. 2 is a side elevational view of the safe, showing the mechanism in vertical sectional view.

Fig. 3 represents a fragmentary sectional view disclosing the foundation for the safe.

Fig. 4 represents a diagrammatical view disclosing the electrical connection between the electrical devices involved.

Referring to the drawings wherein like numerals designate like parts, it can be seen that numeral 5 represents the safe shell with the numeral 6 representing the closure or door of the safe with the locking means designated by numeral 7.

In carrying out the present invention a base 8 is provided with a pocket carried therein within which the usual wheels or casters 10 of the safe are disposed. Thus the dove-tail shaped ribs 11 extend through the pocket 9 and the side walls of the pocket 9 are undetached so that when cement 12 is placed in the pocket and sets it will not easily pull loose from the foundation 8, and furthermore this cement will encompass the casters 10 to prevent detachment of the safe from the foundation.

A raised portion 13 extends across the bottom of the pocket 9 and a bore 14 is provided through this raised portion and also through the sides of the foundation 8. An elongated shaft 15 journalled through the bore 14 and is provided with an upwardly disposed arm 16 terminating at its upper end in a laterally

disposed foot 17 disposed inwardly toward the door 6. When this arm 16 is in an elevated position such as shown in Figs. 1 and 2, it will be impossible for the door 6 to be swung to an open position.

A recess 18 is provided in the foundation 8 at a point apart from the pocket 9 and in this recess 18 functions the collar 19 which has an offset point 20 providing a pair of shoulders 21 and 22. A dog 23 is provided with a guide way 24 thereon for slidably receiving the pin 25 at the lower free end of the bell crank 26, the upper end of the bell crank 26 being attached at one end of the coiled spring 27 extending from the support 28. At the lower free end of the bell crank 26 is the armature for the electro-magnet 29 which is electrically connected in the manner shown in Fig. 4.

As shown in Fig. 4, the numeral 30 represents a motor, the armature shaft 31 of which drives the worm 32 which is constantly in mesh with the gear 33 on the shaft 34. The shaft 34 carries the eccentrics 35, 36, 37, the eccentrics 35, 36 being provided with shoulders 38, while the eccentric 37 is provided with depressions 39 at a pair of diametrically opposite points.

Switches, generally referred to by numerals 40, 41 and 42 are associated with the eccentrics 35, 36 and 37 respectively, each comprising an elongated leaf spring 43 in engagement with its corresponding eccentric, and a short leaf spring 44 for contact with the elongated leaf spring when the elongated leaf spring is released by the corresponding eccentric.

Numerical 45 represents the current supply line to a single pole double throw switch 46, a wire from which extends to the elongated leaf spring 43 of each of the switches 40 and 41. The circuit 47 includes the resistance control 48 for the motor 30 and also the aforementioned electro-magnet 29 with the switch 49.

In operation, assume that the safe locking mechanism is to be set for the desired operation. The arm 51 is set on the resistance control 48 at a position for controlling the speed of the motor 30 so that it will drive the

shaft 34 one-half revolution in a certain number of minutes before releasement of the mechanism; for example—twenty minutes. The timer is now permanently set for a predetermined period of time for releasement and this does not require setting again until the period of time is to be changed.

With the timer thus set, the safe is locked whenever desired by raising arm 16 to the securing position, whereupon the dog 23 will 10 gravitate into a position against shoulder 22. The arm 16 is now bearing against the bar 54 on the closure 53 of the housing 52, thus preventing unauthorized entry.

At any time after the locking of the safe, 15 the safe can be opened by closing the switch 46 (which can be remotely located). This will result in the passage of current thru switch 40 and through circuit 47 to the motor 30, causing the motor 30 to start operating 20 to drive shaft 34 so as to revolve the eccentric 37 which results in the engagement of the leaf spring in the depression 39.

Thus as switch 42 is closed causing the 25 electro-circuit to be energized, the current passes through the switch 49 and through the pilot light 56 which will be located adjacent the switch 46, so that the operator can tell when the safe is unlocked.

The motor continues to operate and the 30 leaf spring 43 of switch 42 is allowed to remain in the depression 39, a period of time, and is then raised so as to break the contact of switch 42. At this point, leaf spring of 35 switch 40 gravitates from the shoulder 38 of the eccentric 35, breaking contact of switch 40 and causing the motor to stop, thus leaving the switch 41 in closed position ready for the operation of the next releasing period.

The alarm 50 is located at some remote 40 point such as in a police station or exteriorly of the building in which the safe is located so as to give warning in an emergency. To operate this alarm, the single pole single 45 throw switch 55 is closed instead of the switch 46. When switch 46 is operated to the exclusion of switch 55, the alarm will not operate.

It is of course to be understood that a 50 spring motor or some other motor means may be employed in place of the electric motor being operated by electrical clutches or the like, without departing from the spirit and scope of the invention as claimed herein-after.

While the foregoing specification sets 55 forth the invention in specific terms, it is to be understood that numerous changes in the shape, size and materials may be resorted to without departing from the spirit and 60 scope of the invention as claimed herein-after.

Having thus described my invention, what I claim as new is:—

1. In combination with a safe and its door, 65 a shaft supported for rocking movement ad-

jacent the safe and having an arm thereon which in one position of the shaft will occupy a position in front of the door to prevent opening of the door, magnetically released latch means for holding the shaft in this position, a circuit for the magnetic means, and time controlled means for controlling the circuit. 70

2. In combination with a lock member, magnetically released latch means for holding the lock member in locked position, a circuit for such means, a normally open switch in said circuit, motor driven means for closing the switch, a circuit for the motor, a pair of switches in the motor circuit, and means 75 operated by the motor for closing one switch after a certain amount of time and simultaneously opening the other of said switches and a hand operated switch for controlling both circuits. 80

3. In combination with a locked member, magnetically released locking means for holding the same in locked position, a circuit for such means, a motor, a circuit for the same, a normally open switch in the magnetic circuit, a shaft driven by the motor, a cam on the shaft for controlling the magnetic switch, a pair of switches for controlling the motor circuit, cams on the motor shaft for controlling said switches, said last mentioned cams 85 acting to close one switch after the other switch has been opened, and a manually operated switch for connecting either one of the last mentioned switches and the first switch to a source of supply. 90

In testimony whereof I affix my signature.
WALTER H. MORRIS.
